UNITED STATES PATENT OFFICE.

GEORGE LOY HOPPING, OF LONGBEACH, CALIFORNIA.

HEAT-REGULATOR.

No. 895,371.

Specification of Letters Patent.

Patented Aug. 4, 1908.

Application filed October 31, 1907. Serial No. 399,995.

To all whom it may concern:

Be it known that I, GEORGE LOY HOPPING, a citizen of the United States, and a resident of Longbeach, in the county of Los Angeles and State of California, have invented a new and Improved Heat-Regulator, of which the following is a full, clear, and exact description.

The invention relates to linotype and other machines requiring an even temperature of molten metal, air or other fluid.

The object of the invention is to provide a new and improved heat regulator, which is simple and durable in construction, exceedingly sensitive in operation, and arranged to control the flow of the gas to the burners, irrespective of the gas pressure.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in all the views.

Figure 1 is a side elevation of the improvement as arranged for use on a linotype machine; Fig. 2 is a sectional side elevation of the same, and Fig. 3 is a sectional plan view of the same on the line 3—3 of Fig. 2.

In machines of the class referred to, it is essential that the temperature of the type metal shall be kept at a given point (550 degrees), to obtain good results in the form of perfect type bars from which to print. Higher temperature gives porous slugs that crush under weight of printing machines, and lower temperature gives poor printing faces to the type in the way of imperfectly formed letters, known as chilled faces.

The regulator heretofore used consists of a mercury bulb placed directly under and in front of the metal pot of the linotype, and takes the temperature of the metal as it is forced from the metal pot into the mold. Extending from the bulb upwards and outwards leads a pipe (one-eighth inch gas pipe), to a point about twelve inches away, where it connects with the regulator proper. At this point the gas is piped into the regulator and out again to the burners. The advancing column of mercury, in itself, partly stops the flow of gas when the proper temperature is reached, and recedes when the pot has chilled from putting in more pigs of

metal, or drafts, or less gas pressure, or other causes.

The gas pressure must be maintained at a very low point—1½ inches water pressure. More pressure than this will displace the mercury and allow the gas to continue on to the burners, and as the extra temperature raises the mercury higher it is forced out along with the gas through the outlet down into the pipes leading to the burners, leaving practically no mercury in the regulator and necessitating the taking out of the burners and pipes and emptying out the mercury to keep it from clogging the gas in the pipes. To control the pressure and hold it this low, a small mercury pressure governor is sent with each single machine or a larger one for several machines. These pressure governors have the same faults as the heat regulator and are easily overcome by sudden extra pressure on the gas mains, which throws out the mercury and allows the pressure to continue on to the machine where it instantly puts the regulator out of commission, as above described. Then sometimes the pressure governor sticks, up or else down, which has the same influence on the machine regulators. Then again at times the pressure in the mains is mostly air and the pressure governors then have to be weighted down to allow more of this poor quality gas to come to the machine in order to maintain the desired temperature. Later on, the gas clears up and comes on without warning through the weighted down pressure governor, and the extra heat raises the mercury higher and higher until it is finally forced out as described above. As a matter of fact, nine out of every ten linotypes are run without automatic heat regulation for the above reasons, although supplied with these governors, the linotype operator governing his heat by turning his gas valve up and down all day long in an endeavor to get the desired results, having become discouraged trying to set his heat regulator and pressure governor so that they will do the work.

The heat regulator presently to be described in detail screws on to the same fittings as the old regulator, using same gas connections and mercury pipe and bulb. With its use no gas pressure governor is necessary and none is used with it at all. It is arranged so that no ordinary gas pressure that may come to it can possibly overcome it.

As shown in the drawings, the cut-off gas chamber A is connected by a supply pipe B with a suitable gas supply, and from the said chamber A leads a pipe C for conducting the gas to the burners employed for heating the metal in the melting pot.

The chamber A is provided at the entrance end of the supply pipe B with a bevelled valve seat D for an oscillating eccentrically-disposed valve E, fulcrumed at E' in the chamber A; and having a curved face E² for practically opening or closing the valve seat D. The oscillating valve E is connected with a depending chain or rod F, supporting at its lower end a float G, floating on the level of a column H of mercury or like fluid contained in a pipe I, connected with the chamber A and with a bulb J. A branch pipe K extends angularly from the pipe I below the level of the column H, and contains a plunger L, terminating in a screw rod L' screwing in the threaded end of the branch pipe K, and normally locked in place by a jam nut N. Now when the jam nut N is loosened, the operator can screw the plunger L in or out in the branch pipe K, to raise or lower the level of the column H of mercury, and thus raise or lower the float G correspondingly. When the desired position is reached the plunger L is locked in place by the jam nut N. The valve E is slightly overbalanced by the float G, so that when the float rises the valve E swings by its own weight into a closing position, and when the float G falls, it swings the valve E gradually open. By arranging the valve E as described, its position is not liable to be disturbed by the gas pressure from the supply pipe. Now when the mercury column H rises, owing to being subjected to a higher temperature, the float G is lifted, and the valve E moves gradually into a closing position, thus gradually cutting off the supply of gas until the mercury stops its upward movement.

When the melting pot is supplied with more metal in the form of solid "pigs", then the temperature of the molten metal in the pot and that of the latter falls, whereby the

temperature of the mercury in the column H is reduced, and consequently falls, so that the float G in descending with the column of mercury acts on the valve E and swings the same correspondingly open, whereby more gas is admitted to the chamber A and to the burners, for raising the temperature of the melting pot.

From the foregoing it will be seen that the valve E moves with the rise or fall of the temperature of the metal in the melting pot, and consequently more or less gas is admitted to the burners for keeping the temperature uniform. Other causes liable to chill the metal in the melting pot, such as cold air blowing in from an open window, produce the same result.

From the foregoing it will be seen that the movement of the valve E is wholly independent of the pressure of the gas, and hence its position is not liable to be disturbed by the gas pressure.

The chamber A is provided with a face plate A', (see Fig. 1), which when removed permits convenient access to the working parts for cleaning or repairing purposes.

Having thus described my invention, I claim as new and desire to secure by Letters Patent:

A heat regulator comprising a cut-off chamber provided with a gas supply, and with a gas outlet, a valve seat at the entrance of the gas supply, said seat being inclined, a mercury column and a float weight supported by the column, a valve having a curved face for co-operating with the inclined seat to cut off the supply of gas, said valve being pivotally mounted, a connection between the valve and the float weight, said valve being returned in normal position by the weight, and means for regulating the height of the mercury in the column.

In testimony whereof I have signed my name to this specification in the presence of two subscribing witnesses.

GEORGE LOY HOPPING.
